United States Patent Office

Des. 178,540
Patented Aug. 14, 1956

178,540

DESK

Wanceslao Sarmiento, Ladue, Mo., assignor to Bank
Building & Equipment Corporation of America, St.
Louis, Mo., a corporation of Delaware

Application January 16, 1956, Serial No. 39,767

Term of patent 14 years

(Cl. D33—7)

FIG. 1.

FIG. 2.

FIG. 3.

FIG. 4.

FIG. 5.

Fig. 1 is a front elevation of a desk showing my new design;

Fig. 2 is a rear elevation;

Fig. 3 is an end elevation viewed from the right of Fig. 2 and from the left of Fig. 1; and,

Figs. 4 and 5 are perspective views taken from the front and rear, respectively.

I claim:

The ornamental design for a desk, substantially as shown.
